ABSTRACT

A spirit level frame is provided with an annular opening. A vial holder includes a pair of spaced clamp members which slip over the frame opening edge and are clamped to the frame, as by tightening screws. To assist the clamp in holding the members together, cooperating ridge and groove means are provided. In addition, projections on the holder and the surfaces of the screws are on an arc of a circle having the same radius as the opening edge for assisting in proper positioning of the holder.

SPIRIT LEVEL WITH CLAMPING ACTION
BACKGROUND AND SUMMARY OF THE
INVENTION

This invention relates to a spirit level, and more particularly to a construction wherein the vial holder is clamped to the level frame in a unique and improved manner.

In accordance with the invention, the level frame is provided with an annular opening. The vial holder includes a pair of spaced clamp members which slip over the frame opening edge and are clamped to the frame, as by tightening screws. To assist the clamp in holding the members together, cooperating rigid and groove means are provided. In addition, locator means on the holder cooperate with the frame opening edge to properly position the holder.

DESCRIPTION OF THE DRAWING

The accompanying drawing illustrates the best mode presently contemplated by the inventor for carrying out the invention.

In the drawing:

FIG. 1 is a plan view of a portion of a level constructed in accordance with the invention;

FIG. 2 is a transverse section taken on line 2—2 of FIG. 1; and

FIG. 3 is a central section taken on line 3—3 of FIG. 2.

DESCRIPTION OF THE PREFERRED EMBODIMENT

As shown in the drawing, the spirit level of the invention may be made with a frame 1 of lightweight tempered aluminum or other suitable material in the form of an I-beam. A circular opening 2 having an annular edge 3 is provided in frame 1 for receipt of a vial holder 4.

Holder 4 is of unitary construction and is made of relatively rigid plastic of any well-known type. As shown, holder 4 comprises a pair of slightly flexible generally planar semi-circular clamping legs 5 which are joined together at their inner portions by an elongated holder base 6 which is shorter than the diameter of opening 2. The outer edges 7 of legs 5 are arcuate and overlie the edge portion of frame opening 2.

Holder 4 is adapted to generally diametrically hold a glass or other suitable level vial 8 therein. For this purpose, a pair of slightly flexible vial clamps 9 extend outwardly from the ends of base 6 radially inwardly from legs 5. Clamps 9 may be of the snap-in type, generally similar to those disclosed in Lawrence A. Johnson U.S. Pat. No. 3,190,010 entitled "SPIRIT LEVEL."

In accordance with the invention, holder legs 5 are spaced apart at their juncture with base 6, and also throughout when in their parallel unclamped position, a distance slightly greater than the thickness of frame 1 adjacent opening 2. This facilitates slipping of the holder legs over the frame opening edge portion. After this is accomplished, and the holder properly positioned and set as will be described, screw means are provided radially inwardly of edge 3 to pull the peripheral portions of clamping legs 5 together into tight engagement with frame 1. As shown, the screw means extend through suitably aligned openings 10 in legs 5, and through frame opening 2, and comprise self-tapping screws 11. The screw means could also comprise a bolt

and nut arrangement without departing from the spirit of the invention.

Any suitable number of screw means may be utilized, it having been found that at least one screw 11 positioned on each side of the holder's transverse center line 2—2 provides excellent holding action.

In some instances, it has been found desirable to supplement the holding power of radially extending clamping legs 5 so that holder 4 will not slide off or ride around opening 2. For this purpose, friction increasing means are provided at the interface between legs 5 and the opening edge portion. In this embodiment, the friction increasing means comprises an annular groove 12 formed on each opposite face of frame 1. Grooves 12 are concentric with and have a larger radius than opening 2. An elongated curved locating ridge 13 is formed on the inner opposed faces of clamping legs 5, with ridges 13 being of the same radius as grooves 12 so that they nest therein, as shown.

Further in accordance with the invention, locating or stop means are provided to limit the radially outward position of holder 4 so that ridges 13 will not overrun grooves 12 during installation. For this purpose, a pair of spaced projections 14 extend outwardly from the end portions of base 6 between legs 5. Projections 14 and the outer portions of screw openings 10 are positioned to be on an arc 15 of a circle of equal radius as opening edge 3. Thus, projections 14 and screws 11 will engage edge 3 and properly locate the holder.

The concept of the invention provides a unique vial holder and clamping arrangement with the level frame. The holder fills approximately one-half of opening 2 and can be selectively adjusted to any desired circumferential position.

Various modes of carrying out the invention are contemplated as being within the scope of the following claims particularly pointing out and distinctly claiming the subject matter which is regarded as the invention.

I claim:

1. A spirit level comprising, in combination:
- a. a level frame having an annular opening therein, said opening defining an edge, and said frame providing an edge portion adjacent said edge,
- b. a relatively rigid vial holder disposed in the said opening and with said holder including a pair of slightly flexible generally planar semi-circular clamping legs,
- c. an elongated base joining the inner portions of said legs and with said base being shorter than the opening diameter,
- d. a vial clamp extending from each end of said base and radially inwardly from said legs,
- e. said legs being spaced apart at their juncture with said base a distance slightly greater than the thickness of said frame,
- f. the outer edges of said legs overlying the said edge portion of said frame opening,
- g. and an annular groove formed on each opposite face of said frame and with said grooves being concentric with and having a larger radius than said opening,
- h. a curved locating ridge formed on the inner opposed faces of the outer edge portions of said legs and nesting in said grooves,
- i. a pair of spaced projections extending outwardly from the end portions of said base between said legs,

- j. and screw means extending through said legs to tighten said holder to said frame,
- k. said projections and the outer surface portion of said screw means being on an arc of a circle having

a radius equal to that of said opening edge so that said projections and said screw means locatingly engage said edge.
